UNITED STATES PATENT OFFICE

CHRISTEN OLSEN, OF CHICAGO, ILLINOIS, ASSIGNOR TO MANZ CORPORATION, OF CHICAGO, ILLINOIS, A CORPORATION OF ILLINOIS

COLOR PRINTING PROCESS

Application filed July 7, 1930. Serial No. 466,369.

This invention relates to improvements in the art of color printing, and more particularly to the printing of several colors in a multi-color press, including a gold impression. The principal object is to provide an improved process whereby many of the difficulties heretofore attending such multi-color printing are eliminated and superior results are obtained.

10 Multi-color printing presses have been used for printing as many as four or five ordinary colors, but the use of a gold impression has greatly increased the difficulties of the printing processes, and it has heretofore 15 been considered impractical to make a gold impression without requiring a separate color press and printing operation. Such gold has usually been applied in the form of a gold bronze powder, which is dusted on a 20 suitably prepared sizing, and requires additional operations for cleaning the bronze. These gold dusting methods have proved to be relatively slow and expensive, and to give somewhat unsatisfactory results, due to 25 the tendency of the flying dust or metallic powder to spread to other parts of the impression. They are particularly objectionable however, as a possible source of injury to the health of those handling the work who 30 may breathe the flying metallic dust in the air, either during the printing and dusting process, and after the work has been finished, as for instance when the work consists of 35 labels from which portions of the metallic powder are usually dislodged during application of the labels to the goods.

In carrying out the present invention, I provide an improved process whereby several colors may be applied in a single multi-color 40 press, including a gold impression in the form of moist gold ink, all of said colors being prepared and applied in an especial rotation so as to make the proper color effect, and at the same time create a surface that 45 has an affinity for a moist gold ink, which is applied last in the rotation of colors.

Referring now to a specific illustration in which my improved invention may be carried out, the single figure of the accompanying 50 drawing shows a label or print 10, part in

perspective and part in section, and in which red areas 11, green areas 12, black areas 13 and gold areas 14 are to appear. I find that it is possible to produce these colors consecutively in a five color press by printing the 55 ordinary colors such as red, green and black first, then applying a suitable sizing, 15, to cover such blank areas 16 as are left uncovered by the previously applied color inks, then last applying the gold in the form of a 60 moist ink. I find that the rotation of the ordinary or base colors, red, green and black, is not essential, although in practice best results have been obtained by rotating them 65 in the order mentioned. It is desirable however, that the color inks referred to be compounded with a suitable mixture of gum adhesive, in addition to their usual content of linseed varnish and dry color. I find that natural gum, as for instance gum copal, is 70 a satisfactory adhesive for this purpose, said gum being added to the color ink in such proportion as is required to provide the desired viscosity and tackiness, depending upon the nature of the original color ink and the 75 speed of the presses, both of which of course may vary considerably with different kinds of work.

In general I find that the addition of gum adhesive so as to constitute approximately 80 10% by weight of the final color ink gives satisfactory results for the described purpose.

After the specially prepared base colors have been applied, I next apply a suitable 85 sizing which consists of a suitable color or colorless ink body, also made of linseed varnish and dry color, with the addition of a gum adhesive of the same character and proportions as is added to the colors previously described. Finally a moist gold ink 90 of the type well known in the art, is applied while they are wet.

A suitable moist gold ink for the purpose is made up of approximately one part by 95 weight of linseed varnish to two parts of fine bronze powder.

I find that the surface formed by the previously applied colors or sizing is of such consistency as to have an affinity for the gold 100

ink and receive it thereon in a permanent, sharply defined impression which, after drying in the usual manner, produces a durable, clean, final product which is much more satisfactory than can be obtained from any methods heretofore utilized for a similar purpose.

While I am aware that moist gold or gold ink of the general type which I used as the base of my gold ink, has been used in ordinary printing, I consider it new to the superimpose such gold ink on the specially prepared colors and sizing while wet, and thus overcome the drying difficulties heretofore encountered in the ordinary printing of gold ink. I find further by the successive printing of the different colors in a single multi-color press as described, the work may be produced at a speed approximately twice the rate of former printing methods, and at the same time produce work which is much better in quality and appearance and more economical in cost to produce.

It will be understood, of course, that my invention is not limited to the use of the colors red, green and black which have been above mentioned as being applied before the gold sizing and gold ink, but that any other combination of colors may be used in a similar manner. The principal feature, therefore, of my method is the rotation of the other color inks before the moist gold is applied.

I claim—

1. The process of multi-color printing including a gold impression which consists of first applying one or more color inks, then a size, and then a gold ink while the color ink and size are wet.

2. The process of multi-color printing including a gold impression which consists in first applying one or more color inks, then applying a size, both said color ink and size including a gum adhesive, and then applying a gold ink while the color ink and size are wet.

3. The process of multi-color printing including red, green, black and gold impression which consists in initially mixing with the red, green and black color inks a gum adhesive and applying them in the rotation mentioned, and then applying a moist gold ink while the first named colors are wet.

4. The process of multi-color printing including red, green, black and gold impression which consists in initially mixing with the red, green and black color inks a gum adhesive, and applying them in the rotation mentioned superimposing a size including a gum adhesive, and then applying a moist gold ink while the first named colors are wet.

5. The process of multi-color printing including a gold impression which consists in first applying one or more color inks, including as an added element a gum adhesive, and

then applying a moist gold ink while the first named colors are wet.

Signed at Chicago, Ill., this 3rd day of July, 1930.
